(57) **CLAIM**

The ornamental design for a cable outlet tube, as shown and described.

DESCRIPTION

FIG. 1 is a perspective view of a cable outlet tube showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and

FIG. 8 is a cross-sectional view taken along the line A-A of FIG. 6; and,

FIG. 9 is a perspective view showing the cable outlet tube in use for reference.

The broken lines shown represent portions of the cable outlet tube that form no part of the claimed design.
